UNITED STATES PATENT OFFICE.

LOTHAR W. FABER, OF NEW YORK, N. Y., ASSIGNOR TO EBERHARD FABER PENCIL COMPANY, A CORPORATION OF NEW YORK.

DESIGN FOR A BRUSH ATTACHMENT FOR ERASERS.

57,219.

Specification for Design.

Patented Mar. 8, 1921.

Application filed September 24, 1920. Serial No. 412,609. Term of patent 14 years.

To all whom it may concern:

Be it known that I, LOTHAR W. FABER, a citizen of the United States, residing in New York city, in the county of New York and State of New York, have invented a new, original, and ornamental Design for Brush Attachments for Erasers, of which the following is a specification, reference being had to the accompanying drawing, forming part thereof.

Figure 1 is a perspective view of a brush attachment for erasers embodying my new

design, the bristles of the brush being shown in outline by dotted lines;

Fig. 2 is a front elevation of the brush attachment, an eraser and the brush being shown in dotted lines, and

Fig. 3 is a side elevation of the brush attachment, eraser and brush as illustrated in Fig. 2.

I claim:

The ornamental design for a brush attachment for erasers, as shown.

LOTHAR W. FABER.
